Denver, Colo.

Application April 12, 1948, Serial No. 20,476

4 Claims. (Cl. 273—86)

1

This invention relates to a game or amusement device in which toy racing vehicles compete with each other on a model race track.

The principal object of the invention is to provide a simple, compact, and highly efficient device by means of which toy racing automobiles can be propelled around the track without any attachments being made to the automobiles themselves.

Another object of the invention is to provide a power-driven mechanism for operating the racers which will induce an element of chance, so that it will be impossible to determine in advance which racer will win any race.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawings and throughout the description.

In the drawings:

Fig. 1 is a plan view of the improved race track;

Fig. 2 is a top view of the device, with the top track plate removed, as taken on the line 2—2, Fig. 3;

Fig. 3 is an enlarged, longitudinal section, taken on the line 3—3, Fig. 1;

Fig. 4 is a fragmentary enlarged horizontal section, taken on the line 4—4, Fig. 3, illustrating a carriage member employed on the improved amusement device;

Fig. 5 is a side view of the carriage member of Fig. 4;

Fig. 6 is a similarly enlarged, detail section, taken on the line 6—6, Fig. 3, illustrating a permanent magnet structure employed in the improved amusement device;

Fig. 7 is a top view of the magnet structure of Fig. 6 taken on the line 7—7; and

Figs. 8 and 9 are horizontal sectional views, taken on the lines 8—8 and 9—9, respectively, Fig. 3.

The entire mechanism is preferably mounted in an ornamental oval cabinet 10 which is covered by means of a dish-shaped race track plate 11 of non-magnetic material such as aluminum, pressed fiber, etc. having upstanding ridges 12 which divide the track into a plurality of run-

2

ways and provided with a "start" and "finish" line 58. In the embodiment shown, there are four runways, designated by the letters A, B, C, and D.

5 A wheeled vehicle, such as a toy racing car 13, is positioned in each runway. Motion is imparted to the cars 13 magnetically, that is, each car carries a block of magnetic material such as "Alnico" 14. The blocks 14 are magnetically attracted by permanent magnets 15, preferably of the horse shoe type, positioned below the track plate 11, there being one magnet for each of the cars 13. The magnets 15 are moved along the center line of each runway and the car's follow therealong.

Each magnet 15 is mounted on the upper extremity of a magnet post 16 extending upwardly from a carriage plate 17. The carriage plates 17 are positioned below guide tracks 18 and are supported thereon by means of a pair of vertical rollers 19. Each carriage plate carries a pair of horizontal rollers 20 which ride against the outer periphery of the track 18.

The tracks 18 are supported below the track plate 11 upon suitable brackets 21 and are arranged at successively higher elevations as the center is approached. Each track 18 is contoured to follow the contour of one of the runways A, B, C, or D.

Each carriage plate 17 is pivotally mounted on a pivot pin 22 in the outer extremity of a telescoping arm 23. Each of the telescoping arms 23 is slidably mounted in a guide sleeve 24 which guide sleeves are mounted in supporting blocks 25 rotatably mounted at the axis of the device.

Each of the arms 23 is constantly pulled into its guide sleeve 24 by means of a tension spring 26. The springs act to maintain the rollers 20 in contact with the tracks 18 so that the magnets 15 will travel a path corresponding to the path of the runways, A, B, C and D. The telescopic arrangement between the arms 23 and the sleeves 24 allows the magnets to follow an oval outline as they rotate about their axis.

The uppermost block 25, for the runway A, is fixedly mounted on a center shaft 27 which is rotatably mounted in, and extends upwardly from a gear frame 28 mounted in the housing 10 below the track plate 11. The second block 25, for the runway B, is mounted on a tubular shaft 29 which surrounds and rotates about the

shaft 27. The third block 25, for the runway C, is mounted on a larger tubular shaft 30 which is rotatably mounted on the tubular shaft 29. The fourth block 25, for the runway D, is mounted on a still larger tubular shaft 31 which rotates about the tubular shaft 30.

A drive disc 32 is fixed upon the lower extremity of the center shaft 27 and on the lower extremity of each of the tubular shafts 29, 30 and 31. Each of the drive discs 32 rests upon and frictionally engages an individual ratchet gear 33. Each of the ratchet gears 33 is formed on a constantly driven gear 34. The driven gears 34 are unattached at their axes so that they may rotate freely. They are individually rotated from four drive gears 35 which are fixed upon a vertical counter-shaft 36, which is rotatably mounted in the gear frame 28. The counter-shaft 36 may be constantly rotated from any suitable source of power. As illustrated, it is driven from an electric motor 37 through the medium of suitable worm gearing 38.

The driven gears 34 rotate constantly. The drive discs 32 rotate intermittently. Rotation is imparted to each drive disc 32 through the medium of a ratchet dog 39, there being one ratchet dog mounted intermediate its extremities on a pivot pin 40 on the lower face of each drive disc. Each dog is shaped to provide a hook 41 at its inner extremity which is positioned to engage the teeth of one of the ratchet gears 33. The hook 41 of each dog is constantly urged into engagement with the teeth of its ratchet gear 33 by means of a suitable tension spring 42 so that the drive discs 32 will rotate as a unit with their respective driven gears 34.

A vertical ratchet release shaft 43 is positioned alongside the series of drive discs 32. A plurality of ratchet-engaging arms 44 project radially from four hubs 45, which are freely rotatable about the shaft 43. The arms 44 are positioned below each of the dogs 39 and each of the dogs is provided with a downwardly extending engaging pin 46 which rotates into engagement with the arms 44.

As illustrated, there are four of the arms 44 for each dog. Therefore, each revolution of each of the drive discs 32 will rotate its respective arm hub 45, 90°, and four revolutions of each disc will impart one complete revolution to its arm hub 45. One of the arms projecting from each hub 45, which will be designated arm 44', is longer than the remaining three arms. These longer arms 44' swing into contact with a vertical stop bar 47 positioned alongside the shaft 43.

The stop bar 47 is slidably mounted in a guide frame 48 and is normally positioned so that it will be contacted by the longer arms 44', but it can be withdrawn from this position to release these longer arms by means of a pull rod 49 and a U-shaped yoke 50. The stop bar 47 is mounted on the forward extremities of the yoke 50 and a handle 51 is mounted on the outer extremity of the rod 49 on the exterior of the housing 10. Compression springs 52 constantly urge the stop bar 47 to its normal arm engaging position.

The results of the races are made uncertain by means of chance cams 53, there being one of the chance cams mounted below each of the drive discs 32. The chance cams 53 are secured on a vertical chance shaft 54 immediately below each of the drive discs. The chance shaft 54 is constantly driven at reduced speed from a compound gear 55 which is rotatably mounted on the outer tubular shaft 31 and driven from a drive

gear 56 on the counter-shaft 36. The compound gear 55 drives a driven gear 57 secured on the shaft 54. Thus, the shaft 54 rotates constantly at a slower speed, and in the opposite direction to the drive discs 32. Each chance cam 53 comprises two flat, cam-shaped arms which extend into the path of the outer extremity of one of the dogs 39 as the latter rotates about the axis of the shaft 27.

The various operating parts are so arranged that when the magnets 15 are aligned so as to position the cars 13 along the start and finish line 58, the longer ratchet-engaging arm 44' of all of the hubs 45 will be in contact with the stop bar 47, and the engaging pins 46 for the hubs 45 will be in contact with the arms 44 and all of the dogs 39 will be held out of engagement with their ratchet gears 33.

Operation

Let us assume that it is desired to start a race. The handle 51 is withdrawn to pull the stop bar 47 out of engagement with the four arms 44'. This allows the springs 42 to snap the hooks 41 of the dogs 39 into engagement with the ratchets. All of the drive discs 32 now start to rotate so as to swing the magnets 15 about the runways to attract the cars 13 therealong.

The positions of the chance cams 53 are unknown at the start of the race. These cams rotate slowly, crossing the paths of the dogs. Certain of the dogs will occasionally pass the cams without touching them. The outer extremities of certain of the other dogs 39 will occasionally strike the chance cams 53 at various points along the lengths of the cams. This swings these dogs 39 out of engagement with their respective ratchet gears 33 so that the drive discs 32 no longer rotate with their respective driven gears 34 and the cars 13 operated thereby, slow down to the slower speed of the chance cams 53. The dogs follow these chance cams forwardly, due to friction between the rotating ratchet gears and the discs 32, until the dogs are released from the chance cams when the dogs will again engage the ratchet gears and move therewith. This chance engagement of certain of the dogs on any of the laps cannot be foretold in advance and the result is the winner cannot be picked in advance.

As each car completes one lap, its engaging pin 46 will engage one of the arms 44 and turn the stop hub 45 of that car 90°. This continues until the car completes its fourth lap, at which time the longer arm 44' will strike the stop bar 47, preventing further rotation of the arms 44 and causing them to tilt the dog 39 out of engagement with its ratchet so as to allow that car to come to rest. This continues until each car completes its fourth circuit, when the cars will all line up along the finish line 58.

The starting rod 49 may be connected with any suitable coin-actuated device, should it be desired to collect a coin for each race.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A toy racing game comprising: a track plate; ridges on said track plate dividing the surface of the latter into a plurality of endless race-

ways; a vehicle positioned in each race-way the path of travel of each vehicle being defined by the adjacent ridges; magnetic material carried by each vehicle; an endless guide track below and following the contour of each race-way; a magnet mounted to travel along each guide track, there being one magnet positioned below each race-way; a vertical center shaft positioned below said plate; a plurality of tubular shafts surrounding said center shaft; an arm extending from said center shaft and supporting one of said magnets; an arm extending from each of said tubular shafts, each arm supporting one of the remaining magnets, said arms being extensible to allow said magnets to follow the contours of their respective guide tracks; a drive disc secured on each of said shafts; a constantly rotating ratchet wheel positioned adjacent each drive disc; a ratchet dog carried by each drive disc and positioned to engage the adjacent ratchet wheel; and a pin projecting from each ratchet dog; a vertical ratchet release shaft positioned alongside said drive discs; a rotatable hub on said release shaft adjacent each drive disc; a plurality of ratchet-engaging arms projecting radially from each hub into the paths of said pins to be engaged by the latter to intermittently rotate said hubs; a movable vertical stop bar positioned in the path of one of the arms of each hub to be engaged by the latter to stop rotation of said hubs at the termination of a revolution to cause the arms on the stopped hubs, when engaged by the pins on said dogs, to release said ratchet dogs from their respective ratchet wheels when said dogs have made a pre-determined number of revolutions.

2. A toy racing game comprising: a track plate; ridges on said track plate dividing the surface of the latter into a plurality of endless race-ways; a vehicle positioned in each race-way, the path of travel of each vehicle being defined by the adjacent ridges; magnetic material carried by each vehicle; an endless guide track below and following the contour of each race-way; a magnet mounted to travel along each guide track, there being one magnet positioned below each race-way; a vertical center shaft positioned below said plate; a plurality of tubular shafts surrounding said center shaft; an arm extending from said center shaft and supporting one of said magnets; an arm extending from each of said tubular shafts, each arm supporting one of the remaining magnets, said arms being extensible to allow said magnets to follow the contours of their respective guide tracks; a drive disc secured on each of said shafts; a constantly rotating ratchet wheel positioned adjacent each drive disc; a ratchet dog carried by each drive disc and positioned to engage the adjacent ratchet wheel; and a pin projecting from each ratchet dog; a vertical ratchet release shaft positioned alongside said drive discs; a rotatable hub on said release shaft adjacent each drive disc; a plurality of ratchet-engaging arms projecting radially from each hub into the paths of said pins to be engaged by the latter to intermittently rotate said hubs; a movable vertical stop bar positioned in the path of one of the arms of each hub to be engaged by the latter to stop rotation of said hubs at the termination of a revolution to cause the arms on the stopped hubs, when engaged by the pins on said dogs, to release said ratchet dogs from their respective ratchet wheels when said dogs have made a pre-determined number of revolutions; and a rotating chance cam for each

of said dogs, said cams being positioned to engage their respective ratchet dogs at intervals to release said dogs from said wheels.

3. A toy racing game comprising: a track plate; ridges on said track plate dividing the surface of the latter into a plurality of endless race-ways; a vehicle positioned in each race-way, the path of travel of each vehicle being defined by the adjacent ridges; magnetic material carried by each vehicle; an endless guide track below and following the contour of each race-way; a magnet mounted to travel along each guide track, there being one magnet positioned below each race-way; a vertical center shaft positioned below said plate; a plurality of tubular shafts surrounding said center shaft; an arm extending from said center shaft and supporting one of said magnets; an arm extending from each of said tubular shafts, each arm supporting one of the remaining magnets, said arms being extensible to allow said magnets to follow the contours of their respective guide tracks; a drive disc secured on each of said shafts; a constantly rotating ratchet wheel positioned adjacent each drive disc; a ratchet dog pivoted intermediate its extremities to each drive disc so as to engage the adjacent ratchet wheel at its one extremity to cause said disc to rotate therewith; a rotating chance shaft positioned in parallel relation to said center shaft adjacent said discs; and chance arms projecting from said chance shaft into the path of the other extremities of said ratchet dogs to engage the latter when the positions of the dogs and the arms coincide to cause the first extremities of said dogs to release said ratchet wheels at indeterminate intervals.

4. A toy racing game comprising: a track plate; ridges on said track plate dividing the surface of the latter into a plurality of endless race-ways; a vehicle positioned in each race-way, the path of travel of each vehicle being defined by the adjacent ridges; magnetic material carried by each vehicle; an endless guide track below and following the contour of each race-way; a magnet mounted to travel along each guide track, there being one magnet positioned below each race-way; a vertical center shaft positioned below said plate; a plurality of tubular shafts surrounding said center shaft; an arm extending from said center shaft and supporting one of said magnets; an arm extending from each of said tubular shafts, each arm supporting one of the remaining magnets, said arms being extensible to allow said magnets to follow the contours of their respective guide tracks; a drive disc secured on each of said shafts; a constantly rotating ratchet wheel positioned adjacent each drive disc; a ratchet dog pivoted intermediate its extremities to each drive disc so as to engage the adjacent ratchet wheel at its one extremity to cause said disc to rotate therewith; a rotating chance shaft positioned in parallel relation to said center shaft adjacent said discs; chance arms projecting from said chance shaft into the path of the other extremities of said ratchet dogs to engage the latter when the positions of the dogs and the arms coincide to cause the first extremities of said dogs to release said ratchet wheels at indeterminate intervals; a ratchet release shaft positioned parallel to said center shaft adjacent said discs; a hub rotatably mounted on said ratchet release shaft opposite the path of each ratchet dog; release arms projecting from each hub into the path of said dogs so that the

latter will rotate their respective hubs; and means for stopping rotation of said hubs so that said release arms will remain stationary in the path of said ratchet dogs to engage and release the latter from said ratchet wheels.
